UNITED STATES PATENT OFFICE.

FRANCIS W. MAXSTADT, OF ALBANY, NEW YORK, ASSIGNOR OF ONE-HALF
TO BERNHARD NUSBAUM, OF SAME PLACE.

SIPHON.

SPECIFICATION forming part of Letters Patent No. 257,825, dated May 9, 1882.

Application filed April 15, 1880. (No model.)

To all whom it may concern:

Be it known that I, FRANCIS W. MAXSTADT, of the city and county of Albany, and State of New York, have invented certain new and 5 useful Improvements in Siphons, of which the following is a specification.

My invention relates to the construction of siphons for drawing liquids; and it consists in combining with a tube a flexible bulb provided with induction and eduction valves for the purpose of adapting it to use for exhausting the air from the tube preparatory to putting the siphon in operation.

My invention also consists in combining with 15 the eduction-valve a movable arm operated by means of an external handle for the purpose of holding said valve in a closed position to stop the flow of liquid at any time when necessary or desirable.

20 In the accompanying drawings, which form a part of this specification, and to which reference is herein made, Figure 1 is a longitudinal section of my improved siphon, showing the movable arm drawn back and away from the eduction-valve; and Fig. 2, a detached sectional view of the eduction-valve, with the movable arm moved up in position for holding the valve closed.

As illustrated in the drawings, A is the tube 30 of the siphon, which I preferably make of vulcanized rubber or other flexible material, as being best adapted to general use; but when desired it may be made of metallic tubing bent in the usual siphon form. Said tube 35 should be made of sufficient length to form the entire short leg and the greater part of the long leg of the siphon.

An elastic bulb, B, is attached to the tube A by the coupling C, which also forms a chamber and seat for the induction-valve D, that is arranged to open toward the bulb. At the opposite end of the bulb B another coupling, E, is attached, which forms a chamber and seat for the eduction-valve F, opening outward 45 from the bulb.

An arm, G, secured to the rock-shaft *g*, running crosswise through the coupling E, is so arranged that the end of it can be turned up, as shown in Fig. 2, to bear against the under 50 side of the valve F and hold it firmly closed.

A handle, H, is secured to the outer end of the rock-shaft *g* for operating the arm G.

The mode of operation is as follows: The open end of the tube A is immersed in the liquid to be drawn off, leaving the bulb B outside of the vessel containing the liquid, with the outer end of the siphon sufficiently below the surface of the liquid to maintain a supremacy of gravity in favor of the liquid in that limb of the siphon. On applying pressure to the bulb B to discharge the air therefrom the induction-valve D closes and prevents the air from the bulb from passing into the tube A, and at the same time the eduction-valve F opens to permit the air from the bulb 65 to escape into the atmosphere. On releasing the pressure the bulb B expands by its resilience, causing the eduction-valve to close and the induction-valve to open, and the bulb to fill with air from the tube A. As fast as 70 the air is exhausted from the tube the atmospheric pressure on the liquid forces it (the liquid) up into the short leg of the siphon, and then, having once passed the highest point at the bend of the tube, the liquid will continue 75 to flow down through the outer leg of the siphon as long as the lower end of that leg is below the surface of the supply. As both of the valves D and F open downward they offer no obstruction to the free outflow of the liquid; 80 but when it is necessary or desirable to stop the flow the arm G can be thrown up to hold the eduction-valve F closed, and by so doing the discharge may be suspended and restored at pleasure.

For convenience in filling bottles and other small-necked vessels, a tapering tube may be fitted to the outer end of the siphon.

What I claim as my invention, and desire to secure by Letters Patent, is—

1. The combination of bulb B and tube A with induction-valve D, eduction-valve F, and a locking device which at will can be made to prevent said valve F from opening.
2. The combination, with the tube A and elastic bulb B, of the induction-valve D, the eduction-valve F, rock-shaft *g*, arm G, and means for operating said rock-shaft and arm to lock said eduction-valve, and thereby cut off the flow of liquid, substantially as set forth.

FRANCIS W. MAXSTADT.
